UNITED STATES PATENT OFFICE.

HARRY NEGBAUR, OF NEW YORK, N. Y., ASSIGNOR TO E & J BASS, INCORPORATED, A CORPORATION OF NEW YORK.

DESIGN FOR STRIP OR BANDING FOR DECORATIVE PURPOSES.

Application filed May 10, 1923. Serial No. 6,122. Term of patent 3½ years.

To all whom it may concern:

Be it known that I, HARRY NEGBAUR, a citizen of the United States, and a resident of the city, county, and State of New York, have invented a new, original, and ornamental Design for Strip or Banding for Decorative Purposes, of which the following is a specification, reference being had to the accompanying drawing, forming a part hereof.

In the drawings:

Fig. 1 is an elevation of the strip or banding for decorative purposes embodying the new design,

Fig. 2 is a section on the line 2—2 of Fig. 1.

Fig. 3 illustrates the design, in differing widths as applied to a substantially cylindrical surface, as on a vase, and

Fig. 4 illustrates the design as applied to a substantially flat object such as a plate. I claim:

The ornamental design for strip or banding for decorative purposes substantially as shown and described.

HARRY NEGBAUR.
